ADJUSTABLE TROTLINE HOLDERJessie Wilbure Glover, P.O. Box 1, Clarksville, Tex.
Filed Nov. 14, 1961, Ser. No. 152,207
2 Claims. (Cl. 43—54.5)

This invention pertains to improvements in trotline holders for use in the storage and handling of trotlines used in fishing. More specifically, the present invention is directed to the provision of a device of this character which is adapted to accommodate a wide range of styles and sizes of fishhooks while retaining all advantageous functional characteristics of nonadjustable devices of this general character.

It has been previously known to supply trotline holders comprised of a slotted outer tube, having an inner hook supporting shaft therein. Such devices have proven extremely useful, but possess the inherent disadvantage that, with the said inner shaft in a fixed location, utility of such device is quite limited as to the size and type of fishhook which may be used therewith. Accordingly, it is one objective of this invention to provide an adjustable trotline holder wherein means is provided to adapt the same for use with a variety of types and sizes of fishhooks.

With the foregoing object in view, it is yet another object of the invention to accomplish this purpose, but to retain maximum simplicity and a minimum number of elements.

An additional object resides in the provision of a storage and dispensing holder for a trotline adapted for use with fishhooks having shank portions of varying lengths, the holder being of the type which includes a slotted outer tube, an inner hook support having a major axis generally parallel with the major axis of the outer tube, and means for adjustment of the location of the inner hook support with respect to the tube, whereby the distance between the slot in the outer tube and the hook support is variable to permit usage of the device with said varying lengths of fishhooks.

Other and further objects and advantages of the present invention will become apparent from a consideration of the following specification when read in conjunction with the annexed drawing, in which:

FIGURE 1 is a side elevational view of a device constructed in accordance with the teachings of this invention;

FIGURE 2 is an end elevational view of the device shown in FIGURE 1;

FIGURE 3 is a cross-sectional view taken substantially along the section line 3—3 of FIGURE 2, looking in the direction of the arrows;

FIGURE 4 is a detailed, vertical cross-section taken substantially along section line 4—4 of FIGURE 3, looking in the direction of the arrow;

FIGURE 5 is a perspective view, on a reduced scale, of the device as shown in the preceding FIGURES; and

FIGURE 6 is a view similar to FIGURE 4 illustrating the adjustment of the device.

Proceeding now to a more precise description of a preferred and exemplary embodiment of the invention, in the several figures of the drawing, the trotline holder is designated in general by character of reference 10. The holder 10 comprises an elongated, hollow tubular main body portion 12 having opposite open ends 14, 16, and is generally divided into a rear handle portion 18 and forward holder portion 20. The main body portion 12 has an elongated, substantially rectangular slot 22 formed therein which extends substantially the full length of the forward holder portion 20 and opens on the end 16.

The handle portion 18 of the main body portion 12

2

is preferably provided with tape winding 24 or other suitable grip means.

A hollow, tubular, elongated hook support 26 is provided, and includes outer end 28 and inner end 30. The hook support 26 is disposed within the main body portion 12 and extends at least the full length of the forward holder portion 20 thereof, the end 28 preferably projecting somewhat beyond the end 16 thereof to provide a locating means for the fishhooks, as appears in more detail below. The hook support 26 is maintained in location, and adjusted, by a pair of longitudinally spaced adjustment means 32 (identical to one another) located adjacent its ends 28 and 30. The adjustment means 32 comprises the means for variance in the location of the hook support, and include elongated, threaded screws 34. Screws 34 are threadedly received in threaded apertures 36 formed in the hook support 26, and extend through coaxial, non-threaded openings 38 in the main body portion 12. The screws 34 have enlarged slotted heads 40 providing outward means for adjustment, and rings 42 are fixed thereto adjacent the inner side of the main body portion 12 and serve to fix the location of the screw with respect to the main body. Thus, since slot 22 is adjacent to the heads 40 of screws 34, it will be seen that means is provided for variance in the distance between the slot 22 and the hook support 26. In FIGURE 4, the hook support is extended to a maximum height, whereas in comparable FIGURE 6, the minimum length has been selected.

As stated above, the device 10 is for use with a trotline T consisting of a length of line L having a plurality of leaders E attached thereto at longitudinally spaced intervals. To the distal end of each leader E is secured a fishhook F having shank S and bend portion B. The end of the line L has a snap hook H thereon which is releasably secured to a connection eye 44 on the handle portion 18 of the main body portion 12.

Closure means for the end 16 of the main body portion 12 is provided and comprises a cap 46 adapted to fit over said end, and having diametrically opposite, L-shaped slots 48 formed in its sides and opening on its end edges. Slots 48 interlock with pins 50 on main body portion 12, as best seen in FIGURE 1, whereby the cap is releasably attached.

In use, and assuming the trotline T to be stored in the device 10, the cap 46 is removed by suitable manipulation and the exposed end of the line L is secured to an upright pole P or the like (FIGURE 5). The user, generally occupying a boat, then moves away from the pole, holding the device 10 in one hand, and permitting the hooks to slide from the device. When it is desired to replace the hooks, this procedure is reversed; that is, the boat is moved toward the pole P, each hook being manually inserted in the device 10 in sequential order.

The manner of placement of the leaders involves placement of bend portion B of hook F over the protruding end 28 of the hook support 26, and sliding the shank S through the slot 22 to an extreme position, while allowing the line and leaders to hang in loose coils below the main body 12. When the final hook F of the series is positioned within the main body portion 12, the cap 46 is replaced, thereby effectively preventing the hooks from slipping from the holder at a later date.

Alteration of the assembly for use with hooks of varying sizes is accomplished through suitable positioning of the hook support 26 through usage of the adjustment means 32. FIGURE 4 shows the extreme upward location of the hook support 26, wherein hooks F having long shanks S are supported while FIGURE 6 shows an extreme depressed position for the accommodation of hooks having a relatively short shank portion. It will be noted that in each case the shank portion S of the

hook F projects outwardly of the main body portion 12 to afford the means for gripping the same during placement therein.

Having described and illustrated one embodiment of this invention in detail, it will be understood that this description and illustration is offered merely by way of example, and that the invention is to be limited only by the scope of the appended claims.

What is claimed is:

1. An adjustable trotline holder comprising:
  - (a) an elongated substantially tubular body portion having a forward holding portion and a handle portion;
  - (b) the forward holding portion having an elongated, substantially rectangular slot therein having an open outer end;
  - (c) an internal, substantially tubular hook support rod disposed within the forward holding portion;
  - (d) adjustable screw means securing the hook support rod within the forward body portion; and
  - (e) the adjustable screw means comprising a plurality of threaded screws, the screws being received in threaded apertures formed in the hook support rod,

and said thread screws being in fixed relation to said body portion whereby rotation of the screws is effective to change the location of the hook support rod with respect to the body portion.

2. An adjustable trotline holder comprising:

- (a) an elongated, substantially tubular body portion;
- (b) said body portion having a slot formed therein opening on one end thereof;
- (c) an elongated hook support rod disposed within the body portion;
- (d) adjustable screw means securing the hook support rod within the body portion; and
- (e) said adjustable screw means extending between and connecting the hook support rod to the body portion and being rotatable to change the location of the hook support rod with respect to the body portion.
